(57) **CLAIM**

The ornamental design for a solar power plant, as shown and described.

DESCRIPTION

FIG. 1 is an upper front right side isometric view of our new ornamental design for a solar power plant in accordance with the present disclosure;

FIG. 2 is a front side elevational view thereof;

FIG. 3 is a back side elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front lower right isometric view thereof;

FIG. 9 is a rear lower left isometric view thereof;

FIG. 10 is a rear upper left isometric view thereof;

FIG. 11 is a rear upper right isometric view thereof; and,

FIG. 12 is a lower isometric view thereof.

The broken lines depict portion of the solar power plant that form no part of the claimed design.

1 Claim, 12 Drawing Sheets
